A PROCESS FOR THE CATALYTIC CON-
VERSION OF HYDROCARBONSWaldemar O. Mitscherling, Bridgeport, Conn., as-
signor to Neon Research of Connecticut, Inc.,
Bridgeport, Conn., a corporation of Connecti-
cut

Application November 27, 1931, Serial No. 577,561

18 Claims. (Cl. 260—156)

The invention relates to a process for the conversion of hydrocarbons into oxygenated derivatives thereof. More particularly it relates to the oxidation of hydrocarbons to form alcohols and 5 ketones and includes correlated improvements and discoveries whereby oxygenated compounds may be produced directly from hydrocarbons.

It is an object of the invention to provide a process for the preparation of oxygenated compounds from hydrocarbons by subjecting a hydrocarbon to the influence of radiations from a rare gas lamp, as for example, a positive column neon, argon or krypton lamp.

Another object of the invention is to provide 15 a process in which hydrocarbons are subjected to the influence of a positive column rare gas lamp in the presence of a catalytic agent and of a conductive material. The term "conductive material" used throughout the specification and 20 claims will be understood to mean a material, as a metal compound, i. e. a compound of a metallic element, which is introduced into the hydrocarbon undergoing treatment and which increases the electrical conductivity thereof or the 25 effective area of the influence of the rare gas lamp.

A further object of the invention is to provide 30 a process whereby alcohols may be obtained from hydrocarbons by subjecting the hydrocarbons to the influence of a positive column rare gas lamp in the presence of a conductive material and of a catalytic material containing an oxidizing agent.

An additional object of the invention is to provide 35 a process for converting hydrocarbons into oxygenated compounds in which the electrical conductivity of the hydrocarbon is increased by the addition thereto of a metal compound and which may be efficiently, readily and economically carried out on a commercial scale.

A still further object of the invention is to provide 40 a conductive material for addition to a hydrocarbon which is to be subjected to the influence of radiations from a positive column rare gas lamp whereby the hydrocarbon is converted into an oxygenated derivative.

Other objects of the invention will in part be 45 obvious and will in part appear hereinafter.

The invention accordingly comprises the several steps and the relation of one or more of such steps with respect to each of the others thereof, which will be exemplified in the process 50 hereinafter disclosed, and the scope of the invention will be indicated in the claims.

For a fuller understanding of the nature and

objects of the invention reference should be had to the following detailed description taken in connection with the accompanying drawing, in which there is shown an apparatus adapted for effecting the conversion of hydrocarbons in accordance with the invention.

In the practice of the invention a hydrocarbon material which may be composed either of aliphatic or aromatic hydrocarbons or their derivatives, but more particularly of aliphatic hydrocarbons and specifically those which are found in a gasoline, may be subjected to the influence of a positive column rare gas lamp, such as a neon, argon or krypton tube, preferably an argon tube, in the presence of a conductive material and of a catalytic material which may be impregnated with a suitable compound. The conversion may also be, and preferably is, carried out with the addition of water.

The reaction may be accomplished by placing 20 a hydrocarbon material, such as ordinary gasoline, into a suitable receptacle, introducing into the hydrocarbon a rare gas lamp, at least a portion of which is surrounded by a container carrying a catalytic material, and adding a conductive material, as a metal compound, such as a composition consisting of copper hydroxide and agar agar dispersed in gasoline. The container may be closed and connected with a reflux condenser. The rare gas lamp is connected to a 25 suitable source of electrical energy and may have impressed thereupon a voltage of from 12,000 to 30 15,000 volts with a current flow of from 15 to 20 milliamperes. The hydrocarbon may be subjected to the influence of the radiations from the 35 rare gas lamp for varying periods of time, depending upon the type of oxygenated compound desired, but under the electrical impress above mentioned a period of from 1 to 2 hours is sufficient to effect conversion. If desired, the nature 40 of the current cycle may be changed by inserting an oxidized aluminum chain in the circuit.

A suitable apparatus for converting hydrocarbon material is that shown in the drawing. It is to be understood that while this apparatus 45 is for conversion by a batch operation, nevertheless the invention is not so limited but contemplates also the conversion of hydrocarbons in a continuous manner.

The apparatus shown comprises a container 1, 50 which may be of non-conductive material, such as glass or the like, in which there may be positioned a foraminous member 2. This member is preferably formed of a metallic material such as, for example, a nickel wire gauze and is adapted

to hold a catalytic material 3. Within the body of the catalytic material there is positioned a rare gas lamp 4, which may be U shaped as shown, or in the form of a coil or other shape as desired. 5 The rare gas lamp may be filled with any of the rare gases, more particularly neon, argon or krypton and is provided with electrodes 5 by means of which electrical energy may be led into and out of the lamp from a suitable source of 10 alternating current having a potential of from 12,000 to 15,000 volts and of about 60 cycles. Upon the container 1 is positioned a lid or closing member 6, having openings 7 and 11 therein which are fitted respectively with a closure 8 and 15 a reflux condenser 9. If desired the container 1 may be wholly or partially surrounded by a metallic material as a gauze of nickel wire, which is grounded.

The conversion of a hydrocarbon material into 20 an alcohol is brought about by introducing into the container 1 a hydrocarbon material, as an ordinary gasoline, and placing therein a positive column argon lamp surrounded by and embedded in a catalytic material containing an oxidizing 25 agent, as a perborate, a perchlorate, a percarbonate etc. and contained in a foraminous member 2. To the hydrocarbon material there may also be added a small amount of water and of a 30 conductive material such as a dispersion of copper hydroxide and agar agar in gasoline. An alternating 60 cycle current having the cycle modified by the presence of an oxidized aluminum chain in the circuit with a potential of about 12,000 volts and a current flow of about 18 milli- 35 amperes is then passed through the rare gas lamp, whereupon the hydrocarbon material will be subjected to the influence of its radiations in the presence of the catalytic material and of the conductive material. The electrical energy is permitted to be impressed for a period of from 1 to 2 40 hours, when the apparatus is electrically disconnected, the rare gas tube and the catalytic material removed and the conversion product separated into components. The separation may be 45 made by distilling the conversion product and collecting the distillates over desired ranges. The hydrocarbon material is according to the foregoing procedure converted into oxygenated compounds, more particularly alcohols and ketones, 50 specifically normal propyl and isopropyl alcohol, the butyl alcohols, the alkyl alcohols, acetone etc.

The catalytic material may be prepared in a 55 number of ways, the requirement generally being that it shall be granular in form, catalytically active and substantially non-conductive per se. It is desirable also that water be present and that the material be impregnated as, for example, with an oxidizing agent.

A preferred form of catalytic material may be 60 prepared by treating an active carbon, for example a granular decolorizing carbon such as "Darco", by washing, then treating with an organic acid such as acetic acid, thereafter washing thoroughly and steaming to remove the residue of the organic acid. The carbon may also be prepared by first treating with a dilute solution of zinc sulphate, washing and then treating with a dilute solution of sodium bisulphite. The carbon so prepared is impregnated with a solution of a substance having an oxidizing character, such as sodium perborate, which has previously been put into colloidal form by boiling with a trace of a dispersing agent, as a gum, such as agar agar, 65 gum acacia, gum tragacanth, or with other suit-

able materials as glue, gelatine, glucose or the like.

Instead of sodium perborate there may be used other perborates, perchlorates, persulphates, percarbonates, bichromates, hydrogen peroxide or other oxidizing agent. The amount of such added material may be about 5 per cent of the weight of the carbon. 5

A catalytic material containing an oxidizing agent, as above prepared, may, while still moist, 10 be placed in the nickel gauze container 2 and utilized for the conversion of hydrocarbon into, for example, an alcohol or alcohols.

Another suitable catalytic material may be prepared by using pumice as the carrying material. 15 The pumice which has been cracked is soaked in a solution of copper sulphate to which may be added sodium hydroxide until the resolution of the copper hydroxide formed has not quite commenced, that is until a blue precipitate is 20 formed as distinct from an initially green precipitate. There may then be added a small amount of sodium bicarbonate in order to throw back the precipitation slightly and to give a gelatinous mixture containing about 1 to 2 per 25 cent of copper sulphate admixed with some copper carbonate and copper hydroxide. The precipitate should have approximately a neutral reaction and the liquid should be slightly acid. In order that the catalytic material may be in the 30 most active form, the treatment must be carried out at a temperature sufficiently low to prevent the formation of a black precipitate and I have found a temperature of 14° C. or below to be suitable. This material may be utilized in the 35 place of the active carbon material above described and in a like manner.

The carbon or other carrying material may be 40 impregnated with materials other than those hereinbefore mentioned, for example compounds such as sodium acid sulphite, ferrous sulphate, nitre-cake, chlor-acetic acid and a sulphocyanate. The impregnation of the carbon with these compounds may be attained in the above 45 described manner.

A metallized carrying material may be prepared by impregnating cracked pumice stone with the copper mixture above mentioned and then placing the pumice so impregnated in a suitable vessel, as a Gooch crucible or the like, removing the soluble compounds and heating to about 130° C. Black copper oxide is thus formed which may be reduced to a spongy form of metallic copper by causing the hot copper oxide to contact with methyl alcohol. The metallized pumice stone is 50 susceptible to oxidation and accordingly should be preserved in an inert medium, for example by covering it with benzol or the like. 55

A similarly impregnated pumice carrying material may be prepared by soaking pumice in a 60 solution of nickel nitrate, adding sodium hydroxide, thus forming nickel hydroxide, removing the pumice from the solution, washing and heating to about 300° C. The pumice containing nickel oxide may be employed in the same 65 manner as the active carbon and copper impregnated pumice previously described.

The catalytic material prepared by any of the foregoing procedures may be rendered more effective by treating with a hydrocarbon material, 70 as a gasoline, and refluxing for a period of several hours prior to utilization in the conversion of hydrocarbons.

The conductive material to be added to the hydrocarbon undergoing conversion may com- 75

prise a metal compound which may be dispersed in a hydrocarbon material with the aid of a dispersing agent such as a gum, more particularly agar agar, gum acacia, gum tragacanth or glue, 5 gelatine, glucose and the like. More particularly, the metal compound may be a suitable hydroxide, oxide, stearate, resinate, oleate etc. which in conjunction, or forming an emulsion with a hydrocarbon material is adapted to increase the electrical conductivity thereof and to render larger 10 the active area of radiations from a rare gas lamp.

This material may be prepared, for example, to contain a copper compound, as copper hydroxide. 15 Copper hydroxide, which may be prepared by adding sodium hydroxide to copper sulphate, may be dispersed in water to which agar agar has been added (this may require a number of hours). Then there is added gradually a hydrocarbon, such as gasolene, and the admixture subjected to repeated shaking. The copper hydroxide forms an emulsion with the hydrocarbon and constitutes the conductive material utilized in the conversion treatment. Furthermore 20 the conductive material may comprise a metallic element, as copper, nickel, etc., in colloidal form, or it may be made up of a plurality of components, as copper and nickel in colloidal condition, or compounds of such elements, as a mixture of the hydroxides of copper and of nickel.

The conductive material may also be prepared from a metal compound as copper hydroxide through the use of triethanolamine or a combination thereof with oleic acid. Thus, for example, 35 copper hydroxide may be emulsified with triethanolamine and introduced into the hydrocarbon or it may be emulsified by means of a triethanolamine oleate. Such emulsions are soluble in a hydrocarbon material. For example 40 5 parts of oleic acid and one part of triethanolamine may be united to form a compound or emulsion to which there is added 0.5 part copper hydroxide. The admixture thus obtained may then be taken up 45 in a hydrocarbon material and utilized in the conversion procedure.

When using an active carbon impregnated with sodium perborate as a catalytic material, and a copper hydroxide emulsion as a conductive material, the hydrocarbon material may be converted 50 in accordance with my procedure utilizing an argon tube and a period of about two hours with the formation of alcohols, more particularly butyl alcohol. Satisfactory results were obtained when 55 using a copper hydroxide conductive material in amounts of from .1 to .001 of 1 percent.

I have also obtained conversion, producing a mixture of propyl, butyl and amyl alcohols when utilizing an argon or a krypton tube with a conductive material comprising barium hydroxide, barium oxide, aluminum stearate, barium resinate, iron resinate, nickel resinate, aluminum resinate or copper resinate, these materials being added to the hydrocarbon undergoing 60 treatment in an amount, for example, of about 0.1 percent. It will be understood that the resinates here referred to are compounds of the resin acids, for example

$\text{Cu}(\text{C}_{20}\text{H}_{29}\text{O}_2)_2$, $\text{Fe}(\text{C}_{20}\text{H}_{29}\text{O}_2)_3$, $\text{Ni}(\text{C}_{20}\text{H}_{29}\text{O}_2)_2$, 65 etc. The oleates, as barium, strontium, iron, copper etc. may also be employed. The oleates, while effective as a conductive material, decompose under the influence of the electric energy. This renders the process less efficient and makes 70 impossible their recovery. The resinates have

been found to be more stable and are to be preferred.

The result obtained, that is the alcohol or the mixture of alcohols, will vary depending upon the variations of the electrical impress. Thus the 5 process may be operated with a 2,000 volt impress and a current of 6 milliamperes or with a 15,000 volt impress and a current of 30 milliamperes, the current being 60 cycle alternating type 10 which may be modified by the placement of an oxidized aluminum chain in the circuit. For the production of isopropyl and butyl alcohols from an ordinary gasolene using an active carbon-sodium perborate catalytic material and a copper hydroxide conductive material, conversion has 15 been obtained through the use of from 12,000 to 14,000 volts with a current flow of not over 20 milliamperes, the duration of treatment being about 1½ to 2 hours.

Since certain changes may be made in carrying out the above process without departing from the scope of the invention, it is intended that all matter contained in the above description shall be interpreted as illustrative and not in a limiting sense.

It is also to be understood that the following claims are intended to cover all of the generic and specific features of the invention herein described, and all statements of the scope of the invention which, as a matter of language, might 30 be said to fall therebetween.

Having described my invention, what I claim as new and desire to secure by Letters Patent, is:

1. A process for the conversion of liquid hydrocarbons into oxygenated compounds which comprises subjecting said hydrocarbons in the presence of a catalytic material containing an oxidizing agent and of a metal compound which increases the electrical conductivity of the hydrocarbon undergoing treatment to the action of 40 radiations from a rare gas lamp.

2. A process for the conversion of liquid hydrocarbons into oxygenated compounds which comprises subjecting said hydrocarbons in the presence of a catalytic material containing an oxidizing agent and of a metal compound which increases the electrical conductivity of the hydrocarbon undergoing treatment to the action of 45 radiations from a positive column rare gas lamp.

3. A process for the conversion of liquid hydrocarbons into oxygenated compounds which comprises subjecting said hydrocarbons in the presence of water, of a catalytic material containing an oxidizing agent and of a metal compound which increases the electrical conductivity of the 55 hydrocarbon undergoing treatment to the action of radiations from a positive column argon lamp.

4. A process for the conversion of liquid hydrocarbons into oxygenated compounds which comprises subjecting said hydrocarbons in the presence of a catalytic material consisting of a carrier and a compound having an oxidizing character and of a copper compound as a conductive material to the action of radiations from a positive column rare gas lamp.

5. A process for the conversion of liquid hydrocarbons into oxygenated compounds which comprises subjecting said hydrocarbons in the presence of a catalytic material consisting of a carrier and a compound having an oxidizing character and of an aluminum compound as a conductive material to the action of radiations from a positive column rare gas lamp.

6. A process for the conversion of liquid hydrocarbons into oxygenated compounds which com-

prises subjecting said hydrocarbons in the presence of a catalytic material consisting of a carrier and a compound having an oxidizing character and of a barium compound as a conductive material to the action of radiations from a positive column rare gas lamp.

7. A process for the conversion of a liquid hydrocarbons into oxygenated compounds which comprises subjecting said hydrocarbons in the presence of water, of a catalytic material consisting of a carrier and a compound having an oxidizing character and of copper hydroxide as a conductive material to the action of radiations from a positive column argon lamp.

15. 8. A process for the conversion of liquid hydrocarbons into oxygenated compounds which comprises subjecting said hydrocarbons in the presence of water, of a catalytic material consisting of a carrier and a compound having an oxidizing character and of aluminum stearate as a conductive material to the action of radiations from a positive column argon lamp.

25. 9. A process for the conversion of liquid hydrocarbons into oxygenated compounds which comprises subjecting said hydrocarbons in the presence of water, of a catalytic material consisting of a carrier and a compound having an oxidizing character and of barium resinate as a conductive material to the action of radiations from a positive column argon lamp.

35. 10. In a process for effecting oxygenation of liquid hydrocarbons, the step which comprises assembling the desired hydrocarbons in the presence of a catalyst containing an oxidizing agent and of a metal compound which increases the electrical conductivity of the hydrocarbon undergoing treatment and under the influence of radiations from a positive column rare gas lamp.

40. 11. A process of converting liquid hydrocarbons into oxygenated compounds which comprises subjecting such hydrocarbons in the presence of a metal compound which increases the electrical conductivity of the hydrocarbon undergoing treatment and a catalytic material containing an oxidizing agent to the action of a positive column rare gas lamp, said catalytic material being composed of an insoluble granular porous substance impregnated with an oxidizing material.

50. 12. A process of converting liquid hydrocarbons into oxygenated compounds which comprises subjecting such hydrocarbons in the presence of a metal compound which increases the electrical conductivity of the hydrocarbon undergoing treatment and a catalytic material containing an oxidizing agent to the action of a positive column rare gas lamp, said catalytic material being composed of active carbon impregnated with an oxidizing material.

60. 13. A process of converting liquid hydrocarbons into oxygenated compounds which comprises subjecting such hydrocarbons in the presence of a metal compound which increases the electrical conductivity of the hydrocarbon undergoing treatment and a catalytic material containing an oxidizing agent to the action of a positive column rare gas lamp, said catalytic material being composed of granular active carbon impregnated with an oxidizing material in a colloidal state.

70. 14. A process of converting liquid hydrocarbons into oxygenated compounds which comprises sub-

jecting such hydrocarbons in the presence of a metal compound which increases the electrical conductivity of the hydrocarbon undergoing treatment and a catalytic material containing an oxidizing agent to the action of a positive column argon lamp, said catalytic material being composed of granular active carbon impregnated with a colloidal mixture of a material belonging to the group consisting of agar agar, gum arabic, gum tragacanth, glue, gelatin and glucose and an oxidizing agent belonging to the group consisting of a perborate, a perchlorate, a persulphate, a percarbonate, a bichromate and hydrogen peroxide.

15. 15. A process of converting liquid hydrocarbons into oxygenated compounds which comprises subjecting such hydrocarbons in the presence of a metal compound which increases the electrical conductivity of the hydrocarbon undergoing treatment and a catalytic material containing an oxidizing agent to the action of a positive column rare gas lamp, said catalytic material being composed of an insoluble porous substance impregnated with a mixture of copper hydroxide, copper carbonate and a small amount of copper sulphate.

20. 16. A process of converting liquid hydrocarbons into oxygenated compounds which comprises subjecting such hydrocarbons in the presence of a metal compound which increases the electrical conductivity of the hydrocarbon undergoing treatment and a catalytic material containing an oxidizing agent to the action of a positive column rare gas lamp, said catalytic material being composed of metallized broken pumice prepared by impregnating with a colloidal mixture of copper hydroxide, copper carbonate and a small amount of copper sulphate, and subsequently reducing to metallic copper, impregnated with an oxidizing material belonging to the group consisting of a perborate, a perchlorate, a persulphate, a percarbonate, a bichromate and hydrogen peroxide.

30. 17. A process for converting liquid hydrocarbons which comprises subjecting said hydrocarbons in the presence of water and a metal compound which increases the electrical conductivity of the hydrocarbon undergoing treatment comprising copper hydroxide and of a catalytic material to the action of a positive column argon lamp, said catalytic material being composed of granular active carbon impregnated with a colloidal material belonging to the group consisting of agar agar, gum acacia, gum tragacanth, glue, gelatin, glucose and with a substance belonging to the group consisting of a perborate, a perchlorate, a persulphate, a percarbonate, a bichromate, hydrogen peroxide, an acid sulphite, ferrous sulphate, nitre-cake, chlor-acetic acid and a sulphocyanate.

40. 18. A process for converting liquid hydrocarbons which comprises subjecting said hydrocarbons in the presence of water and of copper hydroxide as a conductive material and of a catalytic material to the action of a positive column argon lamp under an impress of from 12,000 to 15,000 volts and with a current flow of from 15 to 20 milliamperes for a period of from 1 to 2 hours, said catalytic material being composed of granular active carbon impregnated with sodium perborate.

WALDEMAR O. MITSCHERLING. 70
